UNITED STATES PATENT OFFICE.

MADISON W. REEVES, OF SAYRE, PENNSYLVANIA.

DESIGN FOR A JAR-STAND.

SPECIFICATION forming part of Design No. 33,264, dated September 25, 1900.

Application filed August 30, 1900. Serial No. 28,608. Term of patent 7 years.

To all whom it may concern:

Be it known that I, MADISON W. REEVES, a citizen of the United States, residing at Sayre, in the county of Bradford and State of Pennsylvania, have invented a new and original Design for Jar-Stands, of which the following is a specification.

My invention relates to designs for jar-stands, which is illustrated in the accompanying drawings.

Figure 1 is a side elevation of a jar-stand embodying my invention. Fig. 2 is a top plan view of the same.

My design consists of a table portion A, from the center of which projects a standard B. This table portion A consists of three radiating portions a, having rounded outer ends, and the curved coinciding intermediate portions b. The standard B projects through 20 the table A, and radiating outward from the

standard at an inclination are the supporting-legs C. Projecting from the under side of the table and inclined inward, with their lower ends engaging the legs C, are the braces D. Connecting the lower end of the standard B and the outwardly-inclined legs C are the braces or rods E.

Having thus described my design, what I claim, and desire to secure by Letters Patent, is—

The design for a jar-stand substantially as herein shown and described.

In testimony whereof I have hereunto set my hand in the presence of two subscribing witnesses..

MADISON W. REEVES.
